UNITED STATES PATENT OFFICE.

WALFRID WALLENTHIN, OF ATTLEBORO, MASSACHUSETTS, ASSIGNOR TO EISENSTADT MANUFACTURING COMPANY, OF ST. LOUIS, MISSOURI, A CORPORATION OF MISSOURI.

BRACELET.

1,382,034.

Specification of Letters Patent Patented June 21, 1921.

Application filed January 13, 1919. Serial No. 270,772

To all whom it may concern:

Be it known that I, WALFRID WALLENTHIN, a citizen of the United States, residing at Attleboro, Massachusetts, have invented a 5 certain new and useful Bracelet, of which the following is such a full, clear, and exact description as will enable any one skilled in the art to which it appertains to make and use the same, reference being had to the accompanying drawings, forming part of this 10 specification.

My invention relates to a bracelet and method of making the same, its object being to produce a one piece bracelet which is 15 sufficiently resilient that the ends will separate when the catch is released although the bracelet is formed of gold, silver or base metal which has little or no resiliency when in the form of a flat strip or band. An- 20 other object of the invention is to provide convenient and satisfactory means for forming integral ornamental projections on the outer periphery of the bracelet. Other ob- 25 jects and advantages will appear from the following more detailed description.

In the drawings which illustrate a bracelet formed in accordance with my invention, Figure 1 is a perspective view of a complete bracelet; Fig. 2 a view of a portion 30 of the interior surface of the bracelet showing the means for holding the ends of the bracelet together and for guiding the connecting means into engagement; Fig. 3 shows a fragment of the outer periphery of 35 a bracelet which is provided with ornamental projections; and Fig. 4 is a cross section along the line 4—4 of Fig. 1.

The bracelet is formed from a flat strip of metal by passing the same between rolls 40 adapted to swage a plurality of parallel and preferably substantially semicircular ridges 1 on its inner periphery and to leave relatively thin bridges or webs of metal 7 connecting the bases of the ridge portions. Thus 45 the material is formed into what is substantially a plurality of parallel wires connected by thin webs and the completed construction has substantial resilience so that when formed to cause the ends of the bracelet to 50 normally occupy a position in which they are separated, the ends will automatically return to that position when the catch 5 is operating with the opening 6 is released.

As shown in Fig. 3 guiding wires 3 are 55 slidingly mounted in the grooves in the

inner periphery of the bracelet, being re- 60 tained in the grooves by the semicircular bridges or keepers 4 soldered to the walls of the grooves.

If suitable depressions are formed in one 65 of the coöperating rolls, material of the strip from which the bracelet is made will be forced into these depressions and integral projections 2 will be thereby formed on the other periphery of the bracelet at 70 the same time the ridges are formed on the inner periphery.

The advantages of the resilient character- 75 istics of the above described bracelet will be apparent in that the catch need not be 80 held down when the ends are pulled apart as in two part hinged bracelets; no hinges are necessary and thus the cost of the brace- 85 let is decreased and its convenience en- hanced; and the excellent resiliency makes 90 it possible to separate the ends to a much greater extent than shown in Fig. 1, which illustrates the position automatically as- sumed when the catch is released, thus mak- 95 ing it possible to easily pass the bracelet 100 over the hand and at the same time provide for a sufficiently close fit to the wrist to prevent any danger of the bracelet sliding off while the catch is engaged. Another 105 advantage of the grooved arrangement is that the guiding and connecting wires can be seated in these grooves and thus easily attached to the bracelet without forming any projections on the interior surface, since the diameter of these wires can be made less 110 than the depth of the grooves.

Having fully described my invention, what I claim as new and desire to secure by Letters Patent of the United States is:

1. A bracelet comprising a one piece open 95 band of ductile material provided with in- 100 tegral peripherally disposed resilient ridges adapted to cause the ends to separate in a longitudinal direction when released, means 105 for holding the ends together, and means for guiding and limiting the relative motion of the ends.

2. A one piece bracelet provided with a plurality of longitudinally disposed alter- 110 nate grooves and ridges, guiding wires ex- 115 tending between the ends of the bracelet and adapted to slide in the grooves between the ridges.

3. A one piece bracelet provided with a plurality of longitudinally disposed alter- 115

nate grooves and ridges, guiding wires extending between the ends of the bracelet and adapted to slide in the grooves between the ridges, the diameter of said wires being no greater than the depth of said grooves.

4. A one piece bracelet provided with a plurality of longitudinally disposed alternate grooves and ridges, guiding wires extending between the ends of the bracelet and adapted to slide in the grooves between

the ridges, and a resiliently mounted catch for holding the ends of the bracelet together.

In testimony whereof, I have hereunto set my hand and affixed my seal.

WALFRID WALLENTIN. [L.S.]
